TRANSFER MECHANISM

Harry F. Phillips, Springfield, Mass., assignor to
Bausch Machine Tool Company, Springfield,
Mass., a corporation of Massachusetts

Application March 20, 1947, Serial No. 736,034

2 Claims. (Cl. 29—33)

1

My present invention relates to a mechanism whereby work pieces to be machined may be transferred in ordered sequence through one or more stations relative to machines and may be accurately positioned at each station.

In the mechanism of my invention work pieces are successively placed in starting position by an operator and are then transferred from one position or station to the next without further intervention by the operator except to start or stop the mechanism or the machines associated with it. Any number of mechanisms and their associated machines may be arranged in sequence and the work pieces are then transferred automatically from one mechanism to a succeeding one.

Each transfer mechanism is under the control of the machine associated with it so that a work piece is not moved to the working station until the machine, such as a drilling machine, is ready to start the machining operation at that station and is not moved to the next succeeding station until the machine has completed its operation and is ready to receive a succeeding piece. When transfer mechanisms are arranged in sequence, the starting or loading station of one mechanism must be vacant before the preceding mechanism is set in operation to deliver a work piece.

It will be apparent, therefore, that no work piece can be moved into a station until the machine is ready to receive it and until the machining operation on a preceding work piece has been completed. The successive mechanisms are thereby timed to the slowest machine although each mechanism may itself be otherwise independent.

Inasmuch as each transfer mechanism is a complete and separate entity, any number of mechanisms may be combined with a corresponding number of machines to accomplish any desired number of machining operations and may be readily changed about or adapted to changes in the order or types of machines and machining operations.

In assembling a succession of mechanisms it is sufficient that the work piece may slide or move securely from one transfer mechanism to the next.

The machines which operate on the work pieces may be of any type, such as a drilling machine, boring machine, planer or shaper or profiler, or a machine for turning the work piece to a different position for a succeeding operation, or it may be apparatus for inspecting the work accomplished in preceding machines.

2

The work piece is moved to and through the successive stations of each transfer mechanism by a hydraulically operated reciprocating transfer element having a stroke equal to the distance between the stations. As a piece arrives at a working station it is located accurately by locating devices, such as hydraulically actuated pins, which move into accurately positioned openings or holes in the work piece when it is in correct position. When the work piece is located in a station by the locating pins it is clamped securely in position by hydraulically actuated bushing or clamping plates which hold it throughout the machining operation.

15 The transfer element may carry a transfer pin, or similar mechanism, which is depressed when the clamping or bushing plate is depressed and which may, therefore, move underneath the path of the work piece when the transfer bar moves 20 reversely and to engage a work piece and move it from one station to the next when the clamping plate or element is released.

These various mechanisms are preferably controlled by valves so arranged that each element 25 may move only in its proper sequence and timing. Thus, the valves are so arranged that the clamping plate is lowered into clamping position only when the locating pins or elements have moved to locating position. The transfer element moves 30 in reverse direction when the clamping plate is clamped and the transfer pin depressed. As it reaches its rearmost or starting position it then operates a control valve to cause the clamping plate and the transfer pin to rise and the locating 35 pin to be retracted, whereupon the transfer bar moves forwardly carrying with it the work piece from one station to the next. At the end of its stroke it operates a control valve to permit the locating pin to rise or move to locating position 40 and when this is accomplished to permit the clamping plate to clamp the work piece in its located position.

These hydraulically operated valve mechanisms insure that each of these movements will take 45 place in its proper sequence and only when the preceding operation has been successfully and fully completed.

These hydraulic mechanisms are in turn electrically controlled jointly by the machine associated 50 with the transfer mechanism and by control switches at the loading stations of the mechanism and the one next succeeding. This control circuit releases the hydraulic mechanism to advance a work piece when the machine has completed its operation and withdrawn, when the 55

loading station is loaded and that of the next succeeding machine is empty. It also comprises a starting switch for the machine actuated by the clamping of the clamping mechanism and a switch actuated by the withdrawal of the locating pins to permit forward movement of the transfer element.

The various features of the invention are illustrated, by way of example, in the accompanying drawings in which—

Fig. 1 is a side view of a transfer mechanism embodying a preferred form of the invention, parts being broken away to more clearly show the construction;

Fig. 2 is a plan view, and Fig. 3 is an end view of the mechanism shown in Fig. 1;

Fig. 4 is a transverse section on a larger scale on line 4—4 of Fig. 2, showing the transmission mechanism for the transfer bar and pin;

Fig. 5 is a horizontal section taken on line 5—5 of Fig. 3, showing transmission elements for the clamping plate, transfer bar and locating pins;

Fig. 6 is a vertical sectional view taken on line 6—6 of Fig. 5, of a hydraulic cylinder and connections for operating the bushing or clamping plates;

Fig. 7 is a vertical section taken from the right of Fig. 5 of a hydraulic cylinder and a part of a transfer for the transfer bar;

Fig. 8 is a detail of the transfer bar and transmission;

Fig. 9 is a side view of a certain valve control mechanism;

Fig. 10 is a diagrammatic outline of the hydraulic control valves and connections;

Fig. 11 is a section taken on the line 11—11 of Fig. 5;

Fig. 12 is a wiring diagram showing the controls for the hydraulic valve control system shown in Fig. 10.

Referring to the embodiment of the invention shown in the accompanying drawings, a work piece is placed in the starting position as indicated at 15, Fig. 1, on a pair of supporting rails 16 and 17, Figs. 2, 3 and 4, which extend the full length of the machine. These rails are supported on a frame 18 which in turn is mounted on a cabinet 19, Figs. 1 and 3, which may contain all or part of the control mechanism.

The work piece is moved from the position shown at 15 successively to stations indicated at 20 and 21, two stations being shown by way of example, and thence to a starting station 22 on a succeeding machine 23 by means of a suitable transfer mechanism which moves or slides the work piece on the rails 16 and 17 from one station to the next.

The work pieces are guided against sidewise displacement in moving over the supporting rails 16 and 17 by means of guide rails 24 and 25 mounted above the rails 16 and 17 by means of suitable brackets 26 and 27. The guide rails may be diverged at the entrance ends, as indicated at 28 and 29, in order to receive a work piece even though it may be somewhat displaced.

It will be understood that the guide rails 24 and 25 need not be continuous throughout the length of the machine but may be made in sections and also secured otherwise than by the brackets 26 and 27.

Transfer bar and pin

The transfer mechanism comprises a transfer bar 30 having a pair of grooves in its sides to receive oppositely positioned guide flanges 31 and

32 extending from the supporting rails 16 and 17. These flanges support the transfer bar 30 and enable it to slide longitudinally between the rails 16 and 17 for a limited distance equal to the distance between the respective stations 15 and 20 and 20 and 21. In the advance position of the transfer bar it extends from its rear end, shown at 33 in Fig. 2, to the opposite end of the supporting rails 16 and 17. When in reverse position the end 33 would be at the front or starting end of the rails 16 and 17.

The transfer bar is driven alternately in forward and reverse directions by means of a hydraulically operated piston 34 in a cylinder 35 attached to the side of the frame 18, Figs. 2, 3 and 4. The piston is provided with a stem 36 extending into a casing 37 having an adjusting screw 38 at its end to adjust the limit of movement of the piston and stem.

The piston stem 36 is provided with rack teeth 39 which mesh with pinion teeth 40 on a cross shaft 41, Figs. 3 and 4, extending into the frame 18 and journaled therein in a bearing 42. The shaft 41 may also be journaled in a half bearing 43 in the casing 37. As the piston 34 and stem 36 reciprocate they give alternately reversed rotations to the shaft 41.

At the opposite end of the shaft 41 is secured a pinion 44 which meshes with a rack 45 secured to the undersurface of the transfer bar 30 so that the reciprocating movements of the pistons 34 are transferred through the shaft 41 to reciprocating longitudinal movements of the transfer bar 30.

It will be understood, as indicated by the different diameters of the pinions 40 and 44, that the movement of the piston may be shorter than that of the transfer bar or may be in any relative proportion thereto. Through the alternate reciprocations of the piston in the cylinder 35, the transfer bar is moved forward to the position shown in Fig. 2, or reversely, to a starting position at the starting or front end of the machine.

The transfer bar is below the level of the upper surfaces of the rails 16 and 17 and, therefore, out of contact with the work pieces thereon. To engage and carry forward the work pieces with each forward movement of the transfer bar vertical slidable transfer pins 46, 47 and 48 are provided, there being one for each of the stations 15, 20 and 21. The transfer pins 46 and 47 are spaced a distance equal to the distance between the stations 15 and 20 or 20 and 21. The transfer pin 48 is provided at its upper end with a bifurcated horizontal extension 49, the front end of which is distant from the pin 48 by a distance equal to the distance between the separate stations, this distance being sufficient to cause this extension to project over the end of the machine and to the starting position of the next machine.

The extension piece 49 being bifurcated provides a slot to receive a transfer pin 50 of the succeeding machine 23 so that the work piece may be picked up by the transfer mechanism of the succeeding machine.

The transfer pins 46, 47 and 48 are raised simultaneously before each advance stroke of the transfer bar so as to engage a respective work piece, and are lowered before each reverse movement so as to clear the respective work piece.

During the reverse movement of the transfer bar work pieces in the stations 20 and 21 are clamped onto the rails 16 and 17 by suitable downwardly acting clamping mechanisms which

also serve to lower the transfer pins 46, 47 and 48, and which are unclamped or raised immediately preceding the advance movement of the transfer bar. This same mechanism serves to raise the transfer pins.

Clamping mechanism

The clamping mechanism of the stations 20 and 21 respectively comprises vertically moving clamping plates 51 and 52, the construction and operating mechanisms of which are substantially identical.

Referring more particularly to the clamping mechanism of station 20, the clamping plate 51 is supported by a pair of vertically movable rods or shafts 53 and 54 at diagonally opposite positions of the plate 51 which slide in suitable guiding grooves in a supporting frame 55. The upward movement for unclamping the plate 51 and the downward movement for clamping it are imparted to the lower ends of the supporting and operating rods 53 and 54 by means of a reversely driven shaft 56 extending transversely of the machine below and secured to the frame 18, as shown in Fig. 6, and provided with gear teeth 57 and 58 at its opposite ends that mesh with rack teeth 59 and 60 on the lower ends of the shafts 53 and 54.

The lower ends of the vertical movable rods 53 and 54 extend through or into housings 61 and 62 which are secured to the lower surface of the frame 18 and also carry the ends of the shaft 56 and the gear teeth thereon. Through the cross-shaft 56, therefore, both of the rods 53 and 54 are moved simultaneously and for the same distance with each rocking of the shaft 56.

A rocking movement is imparted to the shaft 56 by means of a hydraulically operated piston 63 in a cylinder 64 to the piston stem of which is attached a rack 65 meshing with suitable gear teeth 66 in the mid part of the shaft 56. In this way the vertical movement of the hydraulic piston 63 is imparted equally to the lifting rods 53 and 54 and uniformly to the clamping plate 51 or 52 respectively, it being understood that each clamping mechanism has its own individual operating piston and transmission mechanism.

Also secured to the clamping plate 51 is a pair of vertical slide rods 67 and 68, Figs. 1 and 2, which extend downwardly into the frame 18 to the position shown in Figs. 1, 3 and 4. These rods 67 and 68 being secured to the plate 51 move upwardly and downwardly with it, being guided by suitable guides 69 in the framework 55.

The rods 67 and 68 extend below the rails 16 and 17, as shown in Fig. 1, and have clamped at their lower ends brackets 70 and 71 which serve to raise and lower the transfer pins 46, 47 and 48 through a suitable transmission mechanism.

As shown more particularly in Figs. 3 and 4 the brackets 70, 71 carry a vertically movable grooved guiding bar 72 which extends below the transfer bar 30 a distance at least equal to the distance between the two stations.

At the lower end of the transfer pin 40 is mounted a roller 73, Figs. 3 and 4, which extends into the groove 74 of the bar 72 so that as the bar 72 is raised and lowered by the bracket 70, rod 61 and clamping plate 51, the transfer pin 46 will be raised and lowered accordingly, at the same time the transfer pin 46 may move with the transfer bar 30, longitudinally of the lifting guide 72, the roller 73 moving longitudinally in the groove 74. In this way the pin 46 is caused to move upwardly when the clamping

plate is raised and downwardly when the clamping plate is lowered in clamping position.

The upward and downward movement of the pin 46 is transferred simultaneously to the pins 47 and 48 by means of a shaft 75, Figs. 2, 3 and 4, carried in the transfer bar 30 and extending longitudinally thereof and having gear teeth that mesh with rack teeth 76 on each of the respective transfer pins so that all rise and lower simultaneously and equally.

It will be apparent, therefore, that the clamping plates control the transfer pins, that the transfer pins are lowered and may be moved reversely to starting position when the clamping plates are down holding the respective work pieces, and that the transfer pins rise to engage their respective work pieces and move them forwardly only when the clamping plates or bushing plates are lifted or unclamped.

Locating mechanism

When a work piece is moved into the station 20 or 21 it is accurately located in position before being clamped so that it may be in exact position for the machining operation at that station. For this purpose the work piece is provided with locating openings, preferably two, which are engaged by locating pins 77 and 78, one for each station, and positioned to move upwardly and fit closely into the locating openings of the work piece when the latter has been brought into the respective station by the transfer bar and pins. Preferably the upper ends of the locating pins 77 and 78 are rounded or pointed so that they will find the locating openings of the work piece if the latter is slightly displaced from the proper position and will thereby move it into the exact position it is to occupy for machining.

The locating pins are raised and lowered through a suitable transmission mechanism by means of a hydraulically operated piston 79 in a cylinder 80 mounted on the lower face of the frame 18 as indicated in Fig. 7. The piston 79 is provided with a stem 81 having rack teeth that mesh with suitable gear teeth on a shaft 82 extending longitudinally of the machine below the respective stations 20 and 21.

The shaft 82 is provided with gear teeth 83 and 84 respectively that mesh with corresponding rack teeth in the locating pins 77 of the respective stations 20 and 21, causing the pins 77 to lower when the piston 79 is raised and, reversely, to raise the locating pins when the piston 79 is lowered, the piston rod 81 being on the opposite side of the shaft from the locating pins 77.

The rocking movement of the shaft 82 is transferred to a second shaft 85 parallel to the shaft 82 by means of a transverse rack bar 86, Figs. 5 and 11, sliding in a housing 87 on the under-surface of the frame 18 and having rack teeth that mesh with gear teeth 88 and 89 respectively on the shafts 82 and 85.

Through the rack bar 86 the movements of the shaft 82 are transferred to the shaft 85. These movements are in turn transferred from the shaft 85 to the locating pins 78 by suitable gear teeth that mesh with rack teeth in the pins 78 so that the pins 78 of both of the stations move simultaneously with the pins 77. In the event that the pins 77 and 78 cannot rise into the locating openings in the work piece, either due to displacement of the work piece or other causes, the pressure on the upper side of the piston 79 will be insufficient and the piston will not be able to drop and lower the piston rod 81.

Hydraulic control mechanism

The transfer elements, the clamping elements and the locating mechanisms are operated in relative sequence by an interlocking hydraulic system.

The system so controls the admission of fluid to the cylinders 35, 64 and 80 that each of the elements operates in its appropriate relation to the others. Thus, before the transfer pin can move to starting position the clamping plates must be lowered, and with them the transfer pins, so that each work piece in any working station is held securely while the transfer pin is free to move reversely. The parts remain in these positions until the transfer bar has completed its rearward movement, thereupon the locating pins are withdrawn and in timed relation thereto the clamping plates are lifted or unclamped raising the transfer pins.

When these operations have been completed fluid is admitted to the cylinder 35 in such a manner as to cause the transfer bar and transfer pins to advance moving each work piece to the next succeeding station. The locating pins thereupon rise to locate the work pieces accurately.

If for any reason the locating pins fail to rise, the clamping plates cannot be lowered and no further operation can take place. If the pins do rise, properly locating the work piece, the clamping plates lower also lowering the transfer pins and remain lowered until the machining operation is completed, thereupon the cycle of operation is repeated.

The fluid under pressure for operating the hydraulic mechanisms and for operating the various fluid control elements is drawn from a supply tank, indicated at 96, by means of a pump 91 driven by a motor 92 and supplied to a supply main 93. The pressure in the supply main 93 is limited by means of a relief valve 94 which opens upon generation of pressure above a predetermined limit to admit fluid from the main 93 through a return circuit 95 leading back to the supply tank 90.

The main 93 leads to a distributing valve 96 controlled alternatively by a pair of electro-magnets 97, 98. The electro-magnet or solenoid 97 is energized by an electrical system when the station 22 of the next succeeding machine is empty and the station at 15 is filled, when the bushing plates are clamped, when the locator pins are raised and when the rear limit switch of the machine tool mechanism is in its back or withdrawn position.

When the solenoid 97 is energized the valve 96 opens communication from pipe 93 through a branch pipe 99 to a distributing pipe 100, all of these pipes being of relatively large size as, for example, $\frac{3}{4}$ " in diameter, through which fluid is supplied through timing valves to the cylinders 35, 64 and 80.

Fluid is also supplied through a smaller control line 101 to a pair of control valves 102 and 103 which are alternately opened and closed by mechanism connected to the clamping plates 51 and 52, the valve 102 being open when the clamping plate is down and closed when the clamping plate is up, and the valve 103, reversely, being closed when the clamping plates are down and open when they are up.

As shown in Figs. 1, 5 and 9, the rod 67 of the clamping plate is extended through the base of the frame 18 and into the cabinet 19 being

guided in a suitable guide box 104 secured to the underside of the base of the frame 18. The rod 67 is positioned above the valve 102 and has an extension 105 to contact with the stem of the valve 102. The lower end of the rod 67 is provided with rack teeth which mesh with a pinion 106 which in turn meshes with a control rod 107 slidable in the guide box 104 immediately above the valve 103 and provided with a push rod 108 to contact with the stem of the valve 103.

Through the above mechanism the valves 102 and 103 are controlled and operated in opposite directions from the clamping plate 51. When the clamping plate is down the valve 102 is moved in such a direction as to permit the passage of pressure fluid from the line 101 to a control line 109 leading to the lower end of a valve 110 and acting to open this valve.

The solenoid 97 being activated the pressure fluid flows from the pipe 99 into a pipe 111 leading to the valve 110 and through this valve through line 112 and forwardly through a check valve 113 and line 114 to the left hand side of the cylinder 35, the cylinder is thereby forced right and, reversely, carries the transfer bar 30 to starting position.

The movements of the transfer bar 30 are transmitted to the hydraulic control system by means of a suitable mechanism which comprises a bevel gear 115, Figs. 1 and 4, fixed on and rotating with the shaft 42 and meshing with a bevel gear 116 fixed on a vertical shaft 117 which extends below the base of the frame 18, as shown in Figs. 1 and 5. The rotation in either direction of the shaft 117 is transmitted by means of bevel gears 118 and 119 to a horizontal shaft 120 and thence through bevel gears 121, 122, to a shaft 123.

On the front end of the shaft 123 is a pinion 124, Fig. 7, which meshes with a gear 125 on a shaft 126 which also carries a control disc 121. Mounted on the disc 127 are a pair of adjustable cams 128 and 129 which, as the disc 127 rotates throughout somewhat less than a full revolution, contact alternatively, and open, hydraulic valves 130 and 131 respectively, Fig. 9.

The mechanism is so arranged that when the transfer bar moves in reverse direction to the starting position the valve 130 will be opened and valve 131 closed at the end of the stroke, and when it moves forwardly to the end of its forward stroke valve 131 will be opened and valve 130 closed.

When the valve 130 is open pressure fluid flows from the line 111 through a branch lead line 132 through the valve 130 and thence to line 133 through a control valve 134, opening this valve. Fluid then flows from the line 111 through a branch line 135 and through the open valve 134 and line 136 to the lower ends of clamping cylinders 64 raising these cylinders and unclamping the clamps and also lifting the transfer bar pins. The lifting of the bushing clamps serves to reverse the valves 102 and 103, through the mechanism described above, opening valve 103 and closing valve 102. Fluid thereupon flows from the line 101 through a branch line 137 and thence through the open valve 103 to line 138 into the bottom of a control valve 139 and opening this valve. As the valve is opened fluid flows from the branch 135 through the valve and through a branch line 140 to the lower end of the locator pin of cylinder 80, forcing upwardly the piston rod 81 and lowering the locating pins 77 and 78.

At this stage the work piece is unclamped, the locating pins are withdrawn and the transfer pins are raised in position to engage their respective work pieces.

When the locating pins are lowered a limit switch is tripped energizing the solenoid 98 and thus reversing the valve 96, pressure fluid then flows through a pipe 141 and line 142 to the right hand side of the cylinder 35 forcing it to the left to advance the transfer bar and at the same time forcing the fluid from the left hand side of the cylinder 35 reversely through the line 114. The check valve 113 prevents the passage of the fluid directly to the line 112 and forces it through a branch line 143 and a speed controlling valve 144 to the valve 110 and thence through the control valve 96 to an exhaust pipe 145 leading to the tank 90.

When the transfer bar 30 has completed its forward movement the cam 129 will have reached the stem of the valve 131 depressing it and opening the valve. The valve 131 now being opened and valve 130 being closed pressure fluid flows from the line or pipe 100 through a branch line 146 and thence through the valve 131 and delivery line 147 to the lower end of a control valve 148, opening this valve. Fluid then flows from the line 100 through the valve 148 and through a line 149 to the upper end of the cylinder 80 thereby depressing this cylinder and lifting the locating pins 27 when the piston rod 81 is lowered to raise the lowering pin 77.

Corresponding rotational movement is transmitted to a cross-shaft 150 which has gear teeth meshing with rack teeth on the piston rod. From thence the rotation of the shaft 150 is transmitted through a similar rack and pinion arrangement at the end of the shaft to a vertical rack bar 151 immediately above a control valve 152 thereby lowering this valve and opening it.

As the valve 152 opens control pressure fluid is admitted from the line 149 through a branch line 153 and through the valve leading to a line 154 to a control valve 155, opening the latter; thereupon fluid flows from the line 149 through valve 155 and a pressure control valve 156 to a line 157 leading to the upper ends of the clamping piston 64 and thereby depressing this piston and lowering the clamps to clamping position. The transfer pins are also lowered at the same time.

It will be evident from this control, therefore, that the clamping plates cannot lower to clamping position until the locating pins are in fully raised position. If there is any obstruction that would prevent the locating pins from rising and accurately locating the work pieces in position, the clamping plates cannot lower to clamping position.

As the bushing plate clamps the valve 102 is opened and valve 103 is closed tripping a limit switch which controls the movement of the machining mechanism, such as a drilling or boring machine or whatever machine is at the particular station.

The parts remain in this position until the machining operation is completed and the machining mechanism returns to its starting position. As the machining mechanism returns to its starting or back position it trips a limit switch which will again de-energize solenoid 98 and energize solenoid 97. When the loading station 22 of the next machine is empty and a new work piece is placed in the station 15 the cycle of operation is repeated.

Electric control

The electric control for the solenoids 97 and 98 is shown diagrammatically in simplified form in Fig. 12 the positions of control switches being indicated diagrammatically in Fig. 1.

In this diagram electric energy is supplied to a line 158 through a suitable start and stop switch mechanism and transmitted to the solenoid 97 by a branch circuit which comprises in series an electric switch 159 closed when a part is in the starting station 15; a switch 160 which is open when the starting station 22 of the next machine is filled and closed when it is empty; switches 161 and 162 which are closed when the clamping plates are lowered; a switch 163 which is open when the locating pins are down and closed when they are up. Electric energy is, therefore, only supplied to energize the solenoid 97 and permit reverse movement of the transfer bar, when station 22 is empty, station 15 is filled, locating pins are up and clamping plates are down in clamped position. The opposite side of the solenoid 97 is connected through a line 165 to a return main 166.

Electric energy is supplied to the solenoid 98 from the main 158, a switch 164 which is closed when the machining mechanism associated with the particular transfer mechanism is in withdrawn or back position and through a switch 167 which is closed when the mechanism of the succeeding machine is in withdrawn position, the opposite side of the solenoid 98 being connected through a branch 168 to the line 165 and return main 166.

It will be obvious, therefore, that this solenoid cannot be energized to advance a work piece until the next machine is in position to receive a work piece. Any suitable start and stop mechanism may be employed to control the supply of electric energy from a main 169 to the line 158.

As illustrated in Fig. 12 this may comprise a master stop switch 170 in a branch circuit 171 having a shunt circuit 172 containing a starting switch 173. The circuit 171 comprises an electro-magnet 174 which closes a switch 175 from the shunt circuit 172 to the line 158 whenever and while current passes through the line 171.

When both switches 170 and 173 are closed current flows through the branch line 172 energizing an electro-magnet 176 to close a relay switch 177 in a shunt circuit 178. This circuit leads through a control solenoid 179 which when energized closes a switch 180 in the branch 171. As current flows through the two solenoids 176 and 179 the switch 177 is closed and then the switch 180 closes. When switch 180 is closed current flows continuously and at all times through the solenoid 179 maintaining a continuous closed circuit so long as the master stop switch 170 remains closed.

When this circuit has once been established it remains whether the starting switch 173 is closed or open. However, once the master stop switch 170 is opened the circuit is not re-established upon releasing it but the starting switch 173 must again be closed. It will be understood, however, that this is merely one way of establishing a starting and stopping control circuit and that other alternative systems may be employed.

It may be noted also that the switches 161 and 162 may be double switches to control the starting of the machining mechanism upon the completing of the clamping operation.

In the above mechanism it will be observed that the transfer mechanism once started will continue in operation as long as work pieces are

supplied to the starting position or station 15, and that if this position should not be supplied the machine will stop but be in readiness to start immediately upon placing a work piece in the starting station.

No transfer will take place until the receiving position 22 of the next machine is empty and ready to receive a work piece. In the event that any machine should stop as, for example, by the breaking of a drill or tool or for any other reason and should, therefore, not return to its starting position, the transfer mechanisms of an entire set or train will stop until this defect is corrected and the respective machine returns to its original position.

It will be noted also that no machining operation can start until the clamping plates are lowered to clamp the work piece in position and that this clamping operation cannot take place until the locating pins have been lifted to locate the work piece accurately in position for machining. Although the machine will come to a stop even if the work piece is not supplied to the initial position 15, thus preventing a haphazard operation of the apparatus, the various transfer machines can be cleared of the last work piece by closing the switch 159 by hand.

The successive transfer machines do not require absolute accuracy in alignment, it only being necessary that the delivery end of each mechanism as, for example, that from the station 21 to the station 22 should be such that a work piece will slide from the rails of the transfer mechanism to the rails of the next and that it come within the widened ends of the guide rails 24 and 25 of a succeeding machine.

As the mechanism of each transfer machine operates independently of the mechanism of a succeeding machine any difficulties, due to the failure of any particular machine, may be traced to that machine.

As the wiring and hydraulic systems are relatively simple for each machine any difficulty in any machine may be easily identified or traced and corrected.

The fact that each transfer machine is self maintained enables it to be readily adjusted to changes in the assembly line. For example, the positions of a drilling machine, or boring machine, or other type of machine tool may be interchanged, additional transfer machines may be added when it is desired to accomplish additional machining operations, or they may be subtracted from an assembly line when fewer operations are to take place.

The clamping plates or bushings are generally made with an open top so that drilling or boring operations may take place vertically as well as horizontally.

Résumé

A cycle of operation of a mechanism or a train of mechanisms is as follows:

At the beginning of the operation the various machines will be running as, for example, in a drilling machine the drills will be rotating and in their withdrawn or starting position, the clamping plates 51 and 52 will be in lowered position and through the push rod 105 will open the valve 102, Figs. 1 and 10. The transfer pins 40 will also be lowered by the elements 61 and 76 connected to the clamping plates, Figs. 3 and 4, so that they may slide horizontally below the level of the supporting rails 16 and 17.

The locating pins 77 and 78 will also be in locating position and through the transmission

elements 150 and 151, Figs. 5 and 10, will depress and open the hydraulic valve 152. The transfer bar or element 30 will be in its forward position and through the transmission elements 115-127 will depress and open the valve 131.

If the load station 22 of the succeeding machine 23 is empty the switch 160, Fig. 12, will be closed. The switches 161 and 162 are closed by the lowering of the clamping plates, and the switch 163 is closed by the locating pins in raised position, and the switch 164 is closed by the machine elements, such as drills, etc., being in their withdrawn or rearmost position.

If a work piece is now placed in the load station at 15 the switch 159 is closed and a circuit completed through the solenoid 97, whereupon fluid pressure is admitted from the pipes 93 and 99 through the valve 96 to the supply pipe 111, Fig. 10, and thence to the valve 110.

The valve 102 being opened fluid also flows through the line 101, valve 102 and line 109 to the lower part of valve 110, opening this valve. Fluid then flows through the line 112, check valve 113 and line 114 to the left hand side of the cylinder 35 causing the transfer element 30 to move to the left.

As the transfer bar moves to the left it rotates the transmission mechanisms 115-127 to close valve 131 and open valve 130. Fluid thereupon flows from the pipe 111 through the line 132 to the open valve 130 and thence through the line 133 to the lower part of valve 134, opening this valve, whereupon fluid flows through the pipe 111 through the branch pipe 135, valve 134 and pipe 136 to the lower parts of clamping cylinders 64, pushing upwardly the piston 63, Figs. 5 and 6, and through the transmission elements 60-66 raising the clamping plate rods 53 and 54 and also raising the transfer pins to extend above the supporting rails 16 and 17.

As the bushing plate rises the valve 102 is released and closed and the valve 103 is depressed and opened, whereupon pressure fluid flows from the pipe 101 through the branch pipe 137 and thence through the open valve 103 and branch line 138 to the lower part of valve 139, opening this valve. Fluid then flows from the pipe 135 through the opened valve 139 and branch pipe 140 to the locating pin cylinder 80, causing the locating pins 77 and 78 to be lowered through the transmission mechanisms 81-86. As the locating pins are lowered the movement of the piston is transmitted through the transmission elements 150 and 151, Figs. 5 and 10, to depress and close the valve 152. At the same time the switch 167, Fig. 12, is closed by the lowering of the locating pin and the solenoid 98 energized.

Inasmuch as the switches 161 and 162 have been opened by the lifting of the clamping plates, solenoid 97 will be de-energized, the position of the valve 96 will, therefore, be reversed closing the supply of fluid to the pipe 111 and opening it to the pipe 100. Pressure fluid, therefore, flows through the valve 96 to the pipe 100 to the right hand side of the transfer bar of cylinder 35, forcing this bar to the right and the transfer pin in forward direction. The movement is retarded by the closing of the check valve 113 shunting the return fluid through the speed control valve 144. The transfer element, therefore, moves forwardly and as the transfer pins are raised each work piece is advanced from one station to the next.

As the transfer bar moves forwardly the valve 130 is closed and at the end of the movement 75 the valve 131 is opened thus returning these

valves to their initial position. Pressure fluid thereupon flows from the pipe 100 through the branch line 146 and the opened valve 131 to the lower part of the control valve 148, raising and opening this valve. Pressure fluid thereupon flows from the pipe 100 through the valve 148 to the upper end of cylinder 80 causing the locating pin 77 to rise and depressing and opening valve 152.

Upon the opening of the valve 152 pressure fluid flowing through valve 148 and branch line 149 is admitted through and to the valve 152 and line 154 to the lower end of valve 155, opening this valve. Valve 148 still being open, pressure fluid flows through the valve 155 and through a pressure regulating valve 156 and pipe 157 to the upper part of cylinder 64, depressing the piston 63 and the clamping plates and clamping the pieces in position.

It will be apparent that pressure can only be admitted to the clamping plates as long as the valve 148 is opened, and accordingly, only while the locating pins are in raised position.

As the clamps are depressed they release and close valve 103 and depress and open valve 102 through the transmission mechanism above described.

The lowering of the clamping plates also serves to close the starting switch of the machines, such as drilling machines, or boring machines, etc., so that these machines advance to perform a machining operation. As these machines complete their operation and return to starting position the cycle repeats.

Having described the invention, what I claim is:

1. Transfer mechanism for moving a work piece in successive steps from a loading station to a work station of a machine and from said work station to a receiving station which comprises a reciprocating transfer means having means to engage a work piece at the loading station and a work piece at the work station, means to actuate said transfer means forwardly a distance equal to the distance between said loading station and said work station and reversely, locating means for engaging and positioning said work piece at said work station, means for securing said work piece at said work station, means controlled by the loading of a piece at said loading station and by the withdrawal of said posi-

50

tion and securing means to actuate said transfer means forwardly and means positioned to be actuated by a work piece at said receiving station to interrupt forward actuation of said transfer means.

2. Transfer mechanism for moving a work piece from a loading station to a work station and from a work station to a receiving station which comprises work piece supporting and guide rails extending from said loading station to said work station and to a receiving station, a reciprocating element extending longitudinally of said rails and movable forwardly and reversely a distance equal to the distance between said stations, pins carried by and movable with said reciprocating element and movable transversely into and out of position to engage a work piece at each said work station and loading station, positioning means at said work station movable to engage a work piece and place it in position for work, clamping means to secure said work piece in position at said work station, said clamping means being connected to and movable with said pins, fluid operated means to move said reciprocating element forwardly and an electric circuit to control the admission of fluid for the forward movement of said reciprocating element and having a switch positioned to be actuated by a work piece in said loading station for the admission of said fluid and a switch positioned to be actuated by a work piece at said receiving station to prevent the admission of said fluid.
